CLAIM

The ornamental design for an atomizer, as shown and described.

DESCRIPTION

FIG. 1 is a front, top, left perspective view of an atomizer showing the new design;

FIG. 2 is a front, top, right perspective view thereof;

FIG. 3 is a front, bottom, left perspective view thereof;

FIG. 4 is a top plan view thereof;

FIG. 5 is a bottom plan view thereof;

FIG. 6 is a front elevation view thereof;

FIG. 7 is a left side view thereof; and,

FIG. 8 is a top, left side, perspective cross-sectional view along line 8-8 of FIG. 4.

The even length broken lines shown in the drawings illustrate portions of the atomizer that form no part of the claimed design. The uneven length broken lines illustrate the boundary of the claimed design, and form no part of the claimed design.
